CLAIM

The ornamental design for a sign, as shown and described.

DESCRIPTION

FIG. 1 is a front side elevational view of a sign, showing my new design, the back side elevational view being a mirror image thereof;
 FIG. 2 is a left side elevational view thereof, the right elevational view being a mirror image thereof;
 FIG. 3 is a top plan view thereof; and,
 FIG. 4 is a bottom plan view thereof.
